UNITED STATES PATENT OFFICE.

JOHN ERIK PLATON, OF JONKOPING, SWEDEN.

MAGAZINE PENCIL.

Application filed March 15, 1924. Serial No. 699,515.

To all whom it may concern:

Be it known that I, JOHN ERIK PLATON, a subject of the King of Sweden, and resident of Smalandsgatan 30, Jonkoping, in 5 the Kingdom of Sweden, have invented certain new and useful Improvements in Magazine Pencils, of which the following is a specification, reference being had therein to the accompanying drawing.

10 This invention refers to improvements in such magazine pencils using interchangeable leads, pieces of aniline or the like, in which the lead is advanced by means of a needle or the like to the point of the pencil, from a 15 magazine which is formed by a tube detachable from the other parts of the pencil.

The invention is illustrated by the accompanying drawing in which Fig. 1 is an enlarged view showing a longitudinal section 20 of the entire pencil. Fig. 2 is a section on the line 2—2 of Fig. 1. Figs. 3 and 4 show a side view and an end view respectively of a detail. Figs. 5 and 6 show other details, Fig. 5 being a side view of the parts of the 25 pencil which are inside the tube seen in a position at right angles to the position shown in Fig. 1, and Fig. 6 being a side view of one end of the magazine tube. Fig. 30 7 is a side view of the pencil with the magazine tube partly pushed on and Fig. 8 is a section on the line 8—8 of Fig. 7.

All the figures with the exception of Fig. 1 show the pencil in enlarged size.

Referring to the drawing in detail the 35 numeral 1 indicates the magazine casing, 2 the tip for the lead and 3 a neck extending from the tip and adapted to be inserted into the casing 1. Said neck is planed sideways in such manner, that a chamber is formed 40 between said planed surface and the tube wall, which chamber at its rear end is limited by a shoulder 15 in the neck, see Figs. 1 and 7. In the bottom of the chamber, i. e. in the planed surface is made as 45 usual a groove 4 which merges into the channel, leading to the tip of the pencil through which channel the leads are forced forwards to the tip by means of the needle 6. The needle 6 is also here surrounded by a protecting tube 16. For the moving backwards and forwards of the needle the pencil is according to this invention arranged in the 50 following manner.

The protecting tube 16 is surrounded by 55 a tube 20 rotatable on the former. The tube 20 is threaded on its inner surface and

in the threads catches a fastening 21 for the needle. Said fastening which of course may be exchanged for a member formed directly out of the needle, is movable in and guided 60 by a longitudinal groove 22 in the protecting tube, so that the needle may be moved backwards and forwards by rotating the intermediate internally threaded tube 20 in relation to the pencil. This rotation is suitably done by means of a button 23 (see Figs. 3, 4) which is so arranged that it is rotatable and removable in the rear end of the magazine casing tube, where it is connected to the intermediate tube 20. Said 65 tube is retained on the protecting tube by any suitable device for instance by a screw 24 screwed into the rear part of the protecting tube, the head of said screw catching into an enlarged part of the intermediate tube abutting against a shoulder in this member (see Figs. 2 and 5). The bottom 17 of the magazine tube, known from earlier devices, is here fastened to the intermediate tube 20. In order to bring the 70 button 23 into engagement with the intermediate tube, the rear end of said tube is provided in this embodiment with two opposite slots 25, Fig. 2, for a transverse pin 26 or the like at the inner end 27 of the button 23, which end is tube-shaped and intended to be inserted into the magazine tube—see Fig. 4, which shows the button 75 seen from the inner end. For the fastening of the button in the magazine tube 1 this 80 is provided with for instance one, two or more warts 28 arranged to catch into a peripheral groove in the tube 27. The end of the button having been inserted into the magazine tube the warts are brought into 85 engagement with the groove by means of the button being pressed gently, and by rotating it simultaneously the pin 26 is brought into engagement with the slots 25 of the intermediate tube.

The button 23 or a corresponding member may of course be connected to the intermediate tube 20 in many different ways, and the device may besides be altered in many ways within the scope of the invention.

The invention refers further to an improved device for the fastening of the tip member 2 in the tube 1. The manner in which said device is arranged is shown in Figs. 5 and 6. The tube 1 is provided with another pin or wart 30 turned inwards and

intended to catch into a groove 31 running entirely or partly round the neck 3, when this is brought into its position in the tube. To the groove 31 leads a longitudinal groove 32 through which the pin or wart is brought into the groove 31, when the tube 1 is pushed over the neck 3. From the position shown in Fig. 7 the wart 30 enters the groove 32 by a slight turning of the tube 1 in relation to the tip 2, or vice versa. The tip 2 being in its position in the tube 1 it is locked by an automatic lock. Said lock may for example consist of a flat spring 33 sunk into and fastened to the neck, which spring is provided with a projection or a bend 34, which may snap into a longitudinal slot 35 in the tube. When the tip is to be loosened, the spring is pressed down, preferably by the nail, and the tube is for that purpose provided with a slot 36 crossing the other. The tip is thereafter turned in relation to the tube until the pin or wart 30 comes opposite the groove 32, and then the tip and the tube may be brought apart. For the insertion of the leads into the chamber between the planed surface of the neck and the wall of the tube 1 the shoulder 15 is provided with an opening 40. (Fig. 8). Through said opening each lead may slide into the chamber when the opening is turned downwards. According to this invention the opening may be shut in order to prevent that on one side the leads crowd together in the chamber and on the other side that a lead which has entered the chamber, slides back into the magazine. For this reason the tube wall is provided with a wart 41 turned inwards and pressed out from the material, which wart may either be situated right in front of or on the side of the shoulder. Said wart closes the opening 40, when the tip 2 is locked in the tube 1 by means of the spring 34. When a lead is to be inserted in the chamber, the wart is moved to the side by the tip 2 and the tube 1 being rotated slightly in relation to each other, the spring 34 having been pushed inwards, and thereby the wart, if situated right in front of the shoulder, enters a groove 42 running entirely or partly round the inner end of the tip.

Such an arrangement, that the opening 40 or a corresponding opening for the same purpose is provided with a closing device, which is independent of the position of the

tube in relation to the tip 2 of the lead, falls naturally within the scope of the invention and does not meet any technical difficulties.

Having now described my invention, what I claim as new and desire to secure by Letters Patent is:

1. A magazine pencil of the character described and comprising in combination a magazine member, a lead holding and guiding tip member, said tip member having a neck at its butt end and adapted to be held in the forward end of the magazine section, a lead ejecting needle for advancing the lead from the magazine to the tip, and means for locking the tip member in the magazine member, said means comprising an internal seat or projection at the forward end of the magazine member, the neck of the tip having a peripheral groove adapted to be normally engaged by said seat, and a lock means for locking said tip member against turning in relation to the magazine member when in proper position therein. 65

2. A magazine pencil, according to claim 1, and wherein the tip-locking means consists of a flat spring carried by the neck of the tip member, and a longitudinal slot in the magazine member, said spring adapted to snap into said slot, and to be disengaged therefrom by external pressure. 75

3. A magazine pencil according to claim 1 characterized by the neck of the tip member having a chamber formed between the neck and the magazine, and by means for shutting off said chamber from the magazine. 80

4. A magazine pencil according to claim 1, characterized by the neck of the tip member being provided with a chamber and means for shutting off said chamber from the magazine, said means comprising a flange forming a wall between the chamber and the magazine, said wall having a passage for inserting the leads into the magazine, the magazine having an internal projection, said passage adapted to be closed by said projection said projection being brought into and out of closing position by rotation of the tip member relatively to the magazine. 95

In witness whereof, I have hereunto signed my name.

JOHN ERIK PLATON.
